UNITED STATES PATENT OFFICE.

JOHN J. PUTNAM, OF EL PASO, TEXAS.

AUTOMATIC CAR-DUMP.

1,059,761.

Specification of Letters Patent. Patented Apr. 22, 1913.

Application filed May 27, 1912. Serial No. 699,891.

To all whom it may concern:

Be it known that I, JOHN J. PUTNAM, a citizen of the United States, residing at El Paso, in the county of El Paso and State of Texas, have invented certain new and useful Improvements in Automatic Car-Dumps, of which the following is a specification.

My improvement relates to automatic dumper and more particularly to a type of automatic dumper that may be readily and inexpensively adapted and fitted to nearly any form of dump car.

The object is to provide a very simple and positive means to insure a quick and complete dump without the usual shock incidental to the present form of this class of device, wherein some unyielding body secured to the runway is engaged by a certain more or less complicated rig forming part of the car equipment.

The improvement, broadly speaking, consists of an automatic superimposed yieldable means for engaging a pivotally mounted car door in a manner tending to raise the said door and effect a "dump" when operating in conjunction with an inclined runway, together with means for returning the said door to the closed position after the dumping operation.

In the drawings Figure 1 is a plan view of the device. Fig. 2 is a side elevation thereof showing the car at the top of the dumping incline and the door raising gear just engaging the door. Figs. 3 and 4 are similar views showing the car in the act of dumping and in the position after the "dump" when the door has been released by the raising device and the car started on its way again.

Referring more specifically to the construction, the several parts being indicated by numerals, 1 is a car having a pivotally mounted door 2 secured by the arms 3 and pivoted at the point 4. A clip 5 secured to the door shown is adapted to engage under certain conditions a similar clip 6 to be referred to later.

The car is mounted as shown on suitable tracks 7 having somewhere in their length at a point where the dumping is to occur an acute inclined runway 8. An arm 9 is mounted in a bearing 10 the said arm having power actuating link 11 and counter weight 12 all for the purpose of preventing the car from passing the dumping point too

quickly. The link 11 may be connected to any suitable power means.

The clip 6 above referred to is carried by a yieldable carriage 13 mounted upon wheels 14 on the superimposed runways 15 and 16, the runway 15 being disposed at a diverging angle to that of the acute inclined runway 8 and at a converging angle to the portion 17 of the car track proper. The portion 16 of the superimposed runway is disposed as shown for the purpose of arresting the speed of the door opener and elevating it sufficiently to allow the car to pass beneath. Guides 18 and 19 are mounted in swivel blocks 20 and 21 for the purpose of steady- 70 ing the opener and insuring the inclining of the engaging clip 6 at the proper angle during the several operations of engagement and releasing of the car door. The curved blocks 22 and 23 at the maximum points of 75 travel of the opener are obviously for the purpose of limiting its movement while the rope 24 and the weight 25 are for returning the same to the first position as shown in Fig. 2 after the car has passed farther along 80 the track 17.

The operation of the device is as follows: The car is moved to the position, Fig. 2, by any suitable means, either mechanical or man power, and started down the dumping incline 8, the arrester 9 serving to hold the car momentarily in the position, Fig. 3, by means of the power link 11. At the same time the car starts down the dumping incline the clip 6 on the door raising device 90 has engaged the clip 5 on the car door and as their planes of movement diverge the door 2 is raised to the position shown in Fig. 3. After the dump has been effected and the arrester is released and the car allowed to proceed by gravity and when it reaches the position shown in Fig. 4, by reason of the convergence of the planes of travel of the car and the car door raising means, the door is lowered to nearly its closed position, 100 at which point it is released allowing said door to fall by gravity to its completely closed position as shown in Fig. 4.

It will be seen by reference to the construction and the functioning of the engaging and releasing carriage that it may be used to advantage in loading ships, warehouses, etc., with bags, boxes and such cargo as will admit of more or less rough handling and operated independently of the car 110

by simply hooking the goods to be transported upon the upturned V-angle clip 6 as shown in Fig. 2, until the quantity overcomes the returning weight 25 at which time 5 the carriage and the goods would descend by gravity to the point where the V-angle clip 6 was reversed into the A-angle clip 6 as shown in Fig. 4, at which point the goods would be automatically released and 10 dropped into the hold of the ship or warehouse, etc. The clip 6 in the engaging position is substantially in the form of a letter V having its engaging toe upturned, but, by reason of the said clip turning over it assumes substantially the form of a letter A 15 having its engaging toe downwardly turned. The runway could of course be made of any desired length and the guiding swivels disposed so as to release the goods at any desired point, the returning weight 25 returning 20 the carriage to the loading position.

While in the drawings I have attempted to show for the sake of clearness only the elementary features of my improvement, it 25 is obvious that I reserve the right to make such slight changes therein as do not depart from the spirit of my invention.

I claim:

1. The combination of a car mounted 30 upon an inclined runway, a pivotally mounted end door in the said car, an engaging device on the said door, and a yieldable means mounted upon a superimposed runway for engaging the said engaging device in a manner tending to automatically raise the pivotally mounted car door as the car descends the above mentioned inclined runway and to lower and release the same after the dumping operation has been 40 effected.

2. In a device of the character described, the combination of a car mounted upon an inclined runway, a pivotally mounted end door in the said car, a protruding clip on 45 the said door, a superimposed yieldable door opening carriage carrying a protruding clip adapted to engage the first mentioned clip, the said carriage being mounted upon an inclined runway disposed at diverging angles 50 to the dumping portion of the inclined car runway and at converging angles to the remaining portion of the said car runway, the said carriage adapted to travel with the car and a means to resist the said travel with a 55 tendency to return the said carriage to the first position of engagement.

3. In a device of the character described, a carriage mounted upon a superimposed inclined runway, a guiding and limiting 60 means for the carriage, a resisting means to gravity and a protruding clip secured to the said carriage the latter adapted to engage a protruding registering clip on a pivotally mounted car door in a manner 65 tending to raise the latter automatically

when the car is disposed beneath the carriage and upon an inclined diverging runway.

4. In a device of the character described, a superimposed engaging and releasing carriage disposed upon a runway, said carriage having a swivel guiding means disposed near the releasing point; an angle clip secured to the carriage portion presenting a V or engaging hook at one end of the runway and an A or releasing hook at the other end by reason of the travel of the carriage and the fixed position of the guiding swivels. 70 75

5. An automatic dump-car door opener comprising a superimposed yieldable carriage mounted above a car runway, and having an engaging means adapted to engage with a registering clip or the like on a dump-car to raise or open a door in said car. 80

6. The combination of a car mounted upon a runway, an end door in the said car, an engaging device on the said door, and a yieldable means mounted upon a superimposed runway for engaging the said device 90 when the car travels along its runway. 85

7. In a car dumping apparatus the combination of a car feed track, means for receiving a car from the feeding track and guiding it into an inclined dumping position, a movable hook adapted to engage the door of the car, means for guiding the hook along a path above that which the engaged part of the door would take if the hook were not provided, and means for disengaging 100 the hook from the car door when the door is in raised position. 95

8. In a cross-over car dumping apparatus, the combination of a car feed track, a car discharge track, means for receiving a car 105 from the feed track, guiding it into dumping position and permitting it to move onward in the initial direction onto the discharge track, a movable hook adapted to engage the door of the car, and means for guiding the hook along a path above that which the engaged part of the door would follow if the hook were not provided. 110

9. In a cross-over car dumping apparatus, the combination of a car feed track, a car 115 discharge track, means for receiving a car from the feed track, guiding it into dumping position and permitting it to move onward in the initial direction onto the discharge track, a movable hook adapted to engage the door of the car, means for guiding the hook along a path above that which the engaged part of the door would follow if the hook were not provided, and means for automatically releasing the hook from 120 the door as the car passes beyond dumping position. 125

10. In a cross-over car dumping apparatus, the combination of a car feed track, a car discharge track, means for receiving 130

a car from the feed track, guiding it into dumping position and permitting it to move onward in the initial direction onto the discharge track, an inclined rail above the path 5 of the car, a trolley movable along the rail, a hook on the trolley adapted to engage the door of the car to open it as the car and the trolley move, and means for returning the trolley to its initial position after the hook 10 is disengaged from the door.

11. In a cross-over car dumping apparatus, the combination of a car feed track, a car discharge track, means for receiving a car from the feed track, guiding it into 15 dumping position and permitting it to move onward in the initial direction onto the dis-

charge track, an inclined rail above the path of the car, a trolley movable along the rail, a hook on the trolley adapted to engage the door of the car to open it as the car and the 20 trolley move, means for automatically disengaging the hook from the door as the car passes beyond dumping position, and means for returning the trolley to its initial position after the hook is disengaged from the 25 door.

In testimony whereof I affix my signature in presence of two witnesses.

JOHN J. PUTNAM.
